UNITED STATES PATENT OFFICE.

WILLIS R. VANAMAN, OF ATLANTIC CITY, NEW JERSEY.

COMBINED FUSE AND SWITCH BOX.

No. 923,466.

Specification of Letters Patent.

Patented June 1, 1909.

Application filed June 10, 1908. Serial No. 437,653.

To all whom it may concern:

Be it known that I, WILLIS R. VANAMAN, a citizen of the United States, residing at Atlantic City, in the county of Atlantic and 5 State of New Jersey, have invented a certain new and useful Combined Fuse and Switch Box, of which the following is a specification.

This invention relates to terminal cut-outs 10 and especially to the fuse-boxes used on electric-railway cars, and has for its principal object to provide a combined fuse and switch-box which permits of ready insertion and removal of a fuse without the spading 15 of the third-rail shoes, pulling of bus lines, pulling of trolley poles, or the opening of switches.

A further object of the invention is to 20 provide a cushioned contact device for holding the end of the fuse, and which is compact, strong and inexpensive and which 25 enables the fuse to be quickly replaced without danger of electrical shock to the operator.

25 A still further object of the present invention is to improve the structural details of this kind of a fuse box.

Other objects will appear hereinafter.

The invention consists of the improvements 30 hereinafter described and finally claimed.

The nature, characteristic features and scope of the invention will be more fully understood from the following description 35 taken in connection with the accompanying drawings forming part hereof and in which:

Figure 1, is a view in elevation of a combined fuse and switch-box embodying the invention and illustrating the lid or cover 40 thereof in open position. Fig. 2, is a view in cross section of the same and illustrating the lid or cover in closed position. Fig. 3, is a view in cross section drawn to an enlarged scale and illustrating the upper portion 45 of Fig. 2. Fig. 4, is a fragmentary view in section and illustrating a somewhat modified form of fuse clamp. Fig. 5, is a similar view illustrating a further modified form of fuse clamp; and Fig. 6, is a similar 50 view illustrating a still further modified form of fuse clamp.

Referring to the drawings, the combined fuse and switch-box is made up or constructed of non-conductive, fire-proof material and is shown as comprising two parts hinged together as at 3, whereof the part 1, 55

constitutes the box, and 2, the lid or cover. As clearly illustrated, the bottom of the box is open to permit the escape of the arc when the fuse blows, and is provided with a 60 magnetized metallic strip 4, that serves among other purposes to prevent persons from placing their hands inside the box and upon the fuse or terminals. Located at the front of the box 1, there is also a 65 magnetized metallic strip 5. At each end of the box 1, and in the respective upper corners thereof and seated within non-conductive material 6, are terminal blocks 7, of suitable conductive material having there- 70 through apertures 8, adapted for the reception of conducting-leads 9 that may enter through the back ends or top of the box 1. As before stated the lid or cover of this box has hinged relation therewith and the edges 75 10, of this lid 2, are arranged to extend or lap over the meeting edges of the lid and box in order to render the said box watertight and dust-proof.

As shown in Figs. 1 and 2, the lid or 80 cover 2, is shown as being slotted as at 11, to accommodate the travel therethrough of the lock-handle 12, which is operatively connected with a system of levers adapted to lock and unlock the lid 2, with respect to the 85 box 1. As shown this mechanism comprises a lever 13, fulcrumed as at 14, to the lid or cover 2, and having pivotal relation with which are lock-bars 15, adapted to coöperate 90 with openings 16, located in the box sides 1, 90 and shown as being adjacent to the terminal blocks 7. By this arrangement it is merely necessary to move the lock-handle 12, either to the left or to the right in order to unlock or lock the box. Carried by the lid or cover 95 2, is a guard or fender 17, of non-conductive material which is adapted to prevent any arc that may be present within the box from springing thereout while the lid or cover is being opened. In this connection 100 it may be also remarked that the hinges 3, are arranged upon the exterior of the box so that current cannot reach them. Arranged above the lock-handle 12, and the slot 11, and carried by the lid or cover 2, 105 is a hood 18, that serves to prevent water from gaining access to the box interior, and also serves to prevent the handle 12, from being moved or misplaced. Upon the inner side of the lid or cover 2, and arranged to 110 cover practically the entire area thereof is a plate of non-conducting material 19, which

is clearly shown in the drawings, and serves to protect the system of levers above described from being attacked by any arc that may be present within the box, and at the 5 same time serves to prevent such arc from escaping through the slot 11. Also carried by the lid or cover 2, are the fuse clamping devices of the invention. As shown these devices 20, comprise cage-like frames consisting of four posts 21, 22, 23, and 24, extending from a block or base 25, and being provided with a top 26, all of these parts being of non-conductive material. The top piece 26, is apertured as at 27, for the passage therethrough of the beveled portion 28, of the contact block 29, the flanged portion 30, of which is guided by and contained within the cage-like frame.

Arranged adjacent to the contact block 20 29, is a finger piece 31, shown as being extended beyond the cage-like frame and as being provided with a hollow extension 32, adapted to work within a sleeve 33, carried by the base plate 25. Interposed between 25 the said base plate 25, and the finger piece 31, and within the hollow extension 32, and sleeve 33, is a cushion or spring 34, which is adapted to normally press the contact block 29, against the terminal block 7, before 30 described. The fuse 35, which may be a strip of copper or the like is placed in position by having its respective ends inserted between the flanged part 30, of the contact block 29, and the finger piece 31. By the 35 above described construction it will be apparent that should a fuse blow out upon an electric-car it will not be necessary to spade the third-rail shoes, pull the bus line, pull the trolley pole, or open any switches in 40 order to insert a new fuse. On the contrary it will be merely necessary to turn the lock-handle 12, to the left, thus causing the bolts 15, to be disengaged from the apertures 16, in the box 1, and pull the lid or cover 2, 45 outward and thus leave the fuse holding devices free of and in no wise contacting with the conducting-leads 9. By the simple operation of pressing downward the cushioned finger piece 31, a new fuse may be readily, 50 conveniently and expeditiously inserted within the clamping device without danger of being shocked by electrical current.

Several modified forms of fuse clamping devices may be used, and a description will 55 now be given of those modified forms shown in the drawings.

In Fig. 4, the arrangement of parts is the same as above described with the exception that the lead-block 36, is slightly beveled as 60 at 37, and the contact block 38, is beveled as at 39.

In Fig. 5, the contact block 40, is shown as being provided with a threaded extension 41, adapted to coöperate with an interiorly 65 threaded and movable member 42, having

cushioned relation with the base of the cage-like frame. In this case the fuse 35, would be provided with apertures 43, for the passage therethrough of the threaded extension 41.

In Fig. 6, a cartridge fuse 44, is shown as being supported between cushioned members 45, and 46, the member 46, having cushioned relation with the base 25, of the cage-like member, and the member 45, having cushioned relation with an intermediate base 25^a. It is thought that the operation of these various modifications will be readily understood in connection with the foregoing description.

What I claim is:

1. In apparatus of the class described the combination of a box comprising a fixed and a movable element, terminal blocks carried by the fixed element cushioned contact blocks carried by the movable element, and means operatively connected with said contact blocks, for receiving and clamping to place a fuse between said contact blocks.

2. In apparatus of the class described the combination of a box comprising a fixed and movable element, terminal blocks carried by the fixed element and cushioned contact blocks having a fuse therebetween carried by the movable element whereby when 95 said movable element is swung clear of the fixed element the circuit is interrupted between the cushioned contact blocks and said terminal blocks.

3. A terminal cut-out comprising a box 100 having a movable cover, terminal blocks carried by the box, cage-like devices carried by the cover, movable contact pieces guided therein, cushioned finger pieces also guided within said cage and a fuse having its respective ends clamped between the contact and finger pieces of the respective cage-like devices.

4. A terminal cut-out comprising a box having a movable cover, terminal blocks 110 carried within the box, cage-like devices consisting of base plates, top plates and posts fixed to said cover, cushioned contact members operatively connected with respect to said cages and a fuse clamped between 115 the respective contact members.

5. A fuse clamping device comprising a base and top plate, posts interposed between said base and top at each corner thereof, a contact member projected through said top, a finger piece having a hollow projection, a sleeve carried by the base and a cushion interposed between said finger piece and base and within said projection and sleeve.

In testimony whereof I have hereunto 125 signed my name.

WILLIS R. VANAMAN.
